(57) **CLAIM**

The ornamental design for a video camera power source housing for helmet, as shown and described.

DESCRIPTION

FIG. 1 is a top, rear and right side perspective view of a video camera power source housing for helmet showing our new design;

FIG. 2 is a rear elevational view thereof;

FIG. 3 is a right side elevational view thereof;

FIG. 4 is a top plan view thereof; and,

FIG. 5 is a bottom plan view thereof.

The broken lines in the drawing are included for the purpose of illustrating environmental subject matter and form no part of the claimed design.
